FOREIGN PATENT DOCUMENTS

KR 300688229.0000 * 4/2013

Primary Examiner — Paula Allen Greene(74) *Attorney, Agent, or Firm* — Brennan, Manna & Diamond, LLC(57) **CLAIM**

The ornamental design for an interactive urn, as shown and described.

DESCRIPTION

FIG. 1 is a perspective view of an interactive urn showing the new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top view thereof; and,

FIG. 7 is a bottom view thereof.

The broken lines in the drawing depict portions of the interactive urn that form no part of the claimed design.
